Inventor

Lewis Wolf,

By Joshua R. Hora
his Attorney.

UNITED STATES PATENT OFFICE.

LEWIS WOLF, OF McNABB, ILLINOIS.

HARP-ACTION.

1,037,569.

Specification of Letters Patent.

Patented Sept. 3, 1912.

Application filed May 17, 1912. Serial No. 697,875.

To all whom it may concern:

Be it known that I, LEWIS WOLF, a citizen of the United States, and a resident of the city of McNabb, county of Putnam, and 5 State of Illinois, have invented certain new and useful Improvements in Harp-Actions, of which the following is a specification.

My invention relates to improvements in harp actions and has for its object the production of a sharpening device for harps which 10 will be of improved construction and efficient in operation.

Other objects will appear hereinafter.

The invention consists in the combinations 15 and arrangements of parts hereinafter described and claimed.

The invention will be best understood by reference to the accompanying drawing forming a part of this specification, and in 20 which,

Figure 1 is a sectional view through the neck portion of a harp showing a sharpening device, embodying my invention, and Fig. 2 is a section taken on line $\alpha-\alpha$ of Fig. 1.

25 The preferred form of construction, as illustrated in the drawing comprises a spindle 1, the respective ends of which are rotatably mounted in the usual spaced plates 2 of the neck of a conventional harp. Carried

30 at one extremity of the spindle 1 is the sharpening-fork comprising the disk 3 and the diametric outwardly projecting pins 4. Oscillation of the spindle 1 for effecting the "sharpening" desired is secured by means of the

35 operating arm 5 which is threaded upon the spindle 1 midway the extremities thereof. The portion 6 of the spindle 1 engaged by the arm 5 is of greater diameter than the remainder of said spindle, and said portion is

40 preferably provided with left-hand screw threads. Threaded upon the opposite ends of said spindle are nuts 7 which abut against opposite sides of the arm 5 to releasably or adjustably lock said arm to said spindle.

45 The end portions of the spindle, that is the portions thereof engaged by the nuts 7 are provided with right-hand screw threads so as to adapt said nuts to effectually lock said arm 5 in position, the latter, as above mentioned, being engaged with left-hand screw threads.

With a construction, as set forth, the arm 5 may be securely locked to the spindle 1 for effecting oscillation thereof in the sharpening 55 operation. When for any reason it is desired to adjust the arm 5 with relation to the

spindle 1, the nuts 7 need only to be retracted, in which event said arm will be free for rotatable adjustment to the desired position. After adjustment said arm may be expeditiously locked in its position of adjustment by moving said nuts into abutting position against the opposite sides of said arm. The construction is simple and economical, and is of high efficiency in use.

While I have illustrated and described the preferred form of construction for carrying my invention into effect, this is capable of variation and modification without departing from the spirit of the invention. I, 79 therefore, do not wish to be limited to the precise details of construction as set forth, but desire to avail myself of such variations and modifications as come within the scope of the appended claims.

Having described my invention what I claim as new and desire to secure by Letters Patent is:

1. In a sharpening device for harps, a rotatable spindle; a sharpening-fork carried by 80 said spindle; an operating arm threaded on said spindle; and nuts threaded on said spindle for adjustably locking said operating arm to said spindle, substantially as described.

2. In a sharpening device for harps, a rotatable spindle; a sharpening-fork carried by 85 said spindle; an operating arm threaded on said spindle; and means adjustably secured to said spindle and abutting opposite sides of said arm for adjustably locking the latter to said spindle, substantially as described.

3. In a sharpening device for harps, a rotatable spindle; a sharpening-fork carried by 90 said spindle; an operating arm threaded on said spindle, the portion of said spindle engaged by said operating arm being of a diameter larger than that of the remainder of said spindle; and nuts threaded on said spindle for locking said operating arm to 100 said spindle, substantially as described.

4. In a sharpening-device for harps, a rotatable spindle; a sharpening-fork carried by 105 said spindle, said spindle intermediate its ends being formed with a portion of a diameter greater than that of the remainder of said spindle; an operating arm threaded on said enlarged portion of said spindle; and nuts threaded on said spindle abutting opposite sides of said operating arm for adjustably locking the latter to said spindle, substantially as described.

5. In a sharpening device for harps, a rotatable spindle; a sharpening-fork carried by said spindle, said spindle intermediate its ends being formed with a portion of a diameter greater than that of the remainder of said spindle; an operating arm threaded on said enlarged portion of said spindle; and nuts threaded on said spindle abutting opposite sides of said operating arm for adjustably locking the latter to said spindle,

said enlarged portion of said spindle being threaded oppositely to the remainder of said spindle, substantially as described.

In testimony whereof I have signed my name to this specification in the presence of 15 two subscribing witnesses.

LEWIS WOLF.
